UNITED STATES PATENT OFFICE.

SOLOMON SIEGEL, OF CHICAGO, ILLINOIS.

VENTILATED GARMENT.

1,261,448.

Specification of Letters Patent.

Patented Apr. 2, 1918.

Application filed January 17, 1918. Serial No. 212,284.

To all whom it may concern:

Be it known that I, SOLOMON SIEGEL, a citizen of the United States, residing at Chicago, in the county of Cook and State of Illinois, have invented certain new and useful Improvements in Ventilated Garments, of which the following is a specification.

This invention relates to improvements in ventilated garments and more particularly to ventilated water-proof garments such as raincoats and the like. One object of the invention is to provide a garment having ventilating means of such a nature that air is circulated from the outer to the inner surface of the garment or vice versa while the garment is in use without the admission of snow, rain or dust from the outer opening in the garment. A further object is to provide a garment, positively ventilated, that is neat and dressy in appearance. More specifically my invention contemplates a garment the garment-forming material of which is overlapped at its points of ventilation and the ventilating means being disposed between the overlapped edges, spaced exterior and interior openings being formed along the edges of the garment-forming material.

With the foregoing and other objects in view the invention consists in the combination and arrangement of parts to be herein-after fully described, pointed out in the appended claims and illustrated in the accompanying drawing which forms a part of this specification and in which—

Figure 1 is a fragmentary view, in elevation, of a garment made according to one embodiment of my present invention.

Fig. 2 is a longitudinal sectional view taken on line 2—2 of Fig. 1.

Fig. 3 is a cross section taken on line 3—3 of Fig. 1.

Fig. 4 is a cross section taken on line 4—4 of Fig. 1.

Fig. 5 is a cross section taken on line 5—5 of Fig. 3.

Fig. 6 is a fragmentary view of a garment illustrating the means of ventilating the same under the arm.

Like reference characters denote corresponding parts throughout the several views.

The reference numerals 1 and 2 denote two pieces of garment-forming material which may comprise the back or the side or other portion of a garment. The respective meeting edges of the two pieces of material are overlapped, the edge 3 of piece 1 being

disposed upon the inside or adjacent the body of the wearer and edge 4 of piece 2 upon the outside surface of the garment. The edges 3 and 4 are both folded inwardly or toward the pieces 2 and 1 respectively as clearly shown in Figs. 3 and 4. Between the strips 1 and 2 I interpose a piece of rubber tubing 5 which is formed with oppositely disposed creases 6 and in said creased portions a plurality of perforations 7 are formed, said tubing being pasted or otherwise secured to the said strips 1, 2 and said tubing being formed, further with a plurality of eyelet-receiving perforations disposed preferably in groups of three, said groups being spaced apart and disposed in alignment with similar eyelet-receiving perforations formed in the strip 1, all of said eyelet receiving perforations carrying the ventilating eyelets 8.

To the strips 1 and 2 at each side of the tubing 5 a tape lining 9 is secured, said lining being pasted direct to the strips 1 and 2 as well as to the tubing. Between the groups of eyelets 8 the pieces of tape lining at each side of the tubing 5 are tacked together or stitched, the tacking being denoted by reference numeral 10. Between the places 10 of tacking, that is laterally opposite the eyelets 8, the strips 1, 2 are partially separated so that the perforated creased portions of the tubing 5 are clearly visible. Fig. 2 of the drawing permits a clear view of the tubing between the edges of the strips where those edges are not stitched together. With the garment in use fresh air will enter through the perforations 7 and eyelets 8 but it is obvious that dust, dirt, rain or snow cannot enter either through the said eyelets or between the strips 1, 2 due to the presence of the perforated tubing 5.

What is claimed is:—

1. A ventilated garment comprising two pieces of material having their meeting edges overlapped, said overlapped edges being stitched together in spaced portions, a perforated tubing disposed between said overlapped garment edges, and ventilating means connecting one of said garment edges and said perforated tubing.

2. A ventilated garment comprising two pieces of material having their meeting edges overlapped, said overlapped edges being stitched together in spaced portions, a perforated tubing disposed between said overlapped garment edges, and ventilating

means connecting one of said garment edges and said perforated tubing, said means being disposed between the stitched portions of said edges.

5. 3. A ventilated garment comprising two pieces of material having their meeting edges overlapped, said overlapped edges being stitched together in spaced portions, a perforated tubing disposed between said overlapped garment edges, and eyelets connecting one of said garment edges and said perforated tubing.

4. A ventilated garment comprising two pieces of material having their meeting edges overlapped, said overlapped edges being stitched together in spaced portions, a doubly creased tubing disposed between said overlapped garment edges and formed with perforations in said creased portions, 15 and ventilating means connecting one of 20 and said garment edges and said creased perforated tubing.

5. A ventilated garment comprising two pieces of material having their meeting edges overlapped, said overlapped edges 25 being stitched together in spaced portions, a doubly creased tubing disposed between said overlapped garment edges and formed with perforations in said creased portions, and ventilating means connecting one of 30 said garment edges and said creased perforated tubing, said ventilating means being disposed in a plane at right angles to the common plane of the creased perforated portions of said tubing.

In testimony that I claim the foregoing as my own I have hereto affixed my signature in the presence of two subscribing witnesses.

SOLOMON SIEGEL.
